UNITED STATES PATENT OFFICE.

JACOB GOLDSTEIN AND ISRAEL BLOCK, OF NEW YORK, N. Y.

DESIGN FOR AN OIL-STOVE.

SPECIFICATION forming part of Design No. 20,139, dated September 9, 1890.

Application filed July 23, 1890. Serial No. 359,691. Term of patent 14 years.

To all whom it may concern:

Be it known that we, JACOB GOLDSTEIN and ISRAEL BLOCK, citizens of the United States, and residents of New York, in the county of New York and State of New York, have invented certain new and useful Improvements in Designs for Gas or Oil Stoves; and we do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of this invention, and is a top view. Fig. 2 is front view. Fig. 3 is a front view of two stoves together, forming a twin stove.

This invention relates to designs for oil or 20 gas stoves; and it consists in the novel form and configuration of the stove as shown and described.

The letter A designates the base of the stove extending outward and downward from 25 its marginal ring *a* in convex form, having the series of open-work bars *b*, and below the same the skirt *c*, having the indented lower edge and extending downward to form the feet *d*.

30 B represents the cylinder-body, and surrounding the same is the flaring open-work crown *E*, having the rim-bead *e* and the marginal flange *f* exterior thereto, said flange ex-

tending slightly downward in curved form. The flaring open-work crown *E* is exteriorly 35 concave in its lower portion with reference to its sectional form, as at *g*, and is in its upper portion convex, as at *g'*.

C is the cylinder-base flaring downward and outward in line with the convexity of the 40 stove-base A, its ornamentation being composed of the leaf-form feet *h*, the leaf-form intermediate extensions *h'*, and the open-work connections *h''*. Below the leaf-form feet are the studs or pedestals *k*, which project upward from the upper marginal ring or band 45 *a* of the base A.

D is the open-work rest-piece of the stove-top, the same having the solid center *m*, the long lateral loops *nn*, and the segment-shaped 50 loops *ll* exterior to said lateral loops.

The same design may be used in forming a double or twin stove, the bases being joined by an open-work brace-connection.

We claim—

55 The design for a gas or oil stove herein shown and described.

In testimony whereof we affix our signatures in presence of two witnesses.

JACOB ^{his} X GOLDSTEIN.
^{mark}
ISRAEL BLOCK.

Witnesses:

PHILIP C. MASI,
CHAS. L. TAYLOR.
